UNITED STATES PATENT OFFICE.

CHARLES COPPOCK, OF FORT THOMAS, ARIZONA TERRITORY.

TONGUE-SUPPORT.

No. 905,658.

Specification of Letters Patent.

Patented Dec. 1, 1908.

Application filed March 10, 1908. Serial No. 420,240.

To all whom it may concern:

Be it known that I, CHARLES COPPOCK, a citizen of the United States, residing at Fort Thomas, in the county of Graham and Territory of Arizona, have invented new and useful Improvements in Tongue-Supports, of which the following is a specification.

This invention relates to improvements in tongue-supports for vehicles, the object of 10 the invention being to provide a simple and inexpensive device of this nature for yieldingly supporting the tongue from the front hounds and preventing the weight of the tongue from falling upon the necks of the 15 draft animal, as well as to relieve the animals from the shocks and jars produced when the vehicle encounters obstructions in the road.

A further object of the invention is to provide a support in the form of a spring carried 20 by the tongue to rest upon the hounds, said spring being adjustable to vary its resistance to the downward movement of the tongue and adapted to be readily applied to existing types of tongues; also to provide a support 25 of this character which is light in weight, which will not interfere with the double trees or the load on the vehicle and which may be allowed to remain in position when not in use without detriment to the use of the 30 vehicle.

The invention consists of the features of construction, combination and arrangement of parts hereinafter fully described and claimed, reference being had to the accompanying drawing, in which:—

Figure 1 is a top plan view showing the application of the invention. Fig. 2 is a transverse section of the same.

Referring to the drawing, the numeral 1 40 designates the front axle, and 2 the front hounds which are secured thereto in the usual way. The tongue 3 extends between the hounds and is pivotally mounted upon a bolt 4.

Extending transversely across the upper and lower surfaces of the tongue are transverse clamping plates 5 and 6, the extended ends of which are formed with openings for the passage of screw bolts 7 arranged vertically on opposite sides of the tongue.

These bolts are provided at their upper ends with eyes 8 forming keepers for the reception and passage of the supporting spring 9. As shown, the spring consists of a metallic strap or leaf in the form of an inverted bow 55 and resting at its ends upon the upper surfaces of the hounds 2.

Riveted or otherwise secured to the center of the underside of the spring is a stop piece 10 which is disposed between the eyes 8 of the bolts and serves to prevent endwise movement of the spring beyond a limited extent. The spring permits a vertical yielding movement of the tongue, while supporting the same in its normal operative position so 60 that its weight will be removed from the necks of the draft animals, the spring also absorbing all shocks and jars and preventing threshing of the tongue resulting from the passage of the wheels over obstacles or rough 65 portions of the road. Nuts 11 engage the upper ends of the bolts and retain the upper clamping plate 5 in position, and similar nuts 12 engage the lower ends of the bolts and retain the lower clamping plate in position, 70 thus securing the supporting spring in a strong and durable manner to the tongue. By means of these nuts the bolts may be adjusted to regulate the pressure of the spring 75 and to increase or diminish its resistance to 80 the downward movement of the tongue, as will be readily understood.

It will be seen that the construction of the device is such as to efficiently secure the objects sought to be obtained, and that the device may be readily applied to the tongues of vehicles already in use.

Having thus fully described the invention, what is claimed as new is:—

1. A tongue support comprising upper and lower clamping plates, a pair of parallel bolts extending through said clamping plates and provided at their upper ends with eyes, a bowed spring extending through the eyes, means coacting with said eyes to limit the 90 endwise movement of the spring, and sets of nuts upon the upper and lower ends of the bolts and bearing upon the respective clamping plates.

2. A tongue support comprising upper and 100

lower clamping plates, a pair of vertical parallel bolts extending through said clamping plates and provided at their upper ends with eyes, a bowed supporting spring extending through said eyes, a stop member upon the spring between the eyes and adapted to limit the endwise movement of the spring, and sets of nuts upon the upper and lower

ends of the bolts and bearing against the respective clamping plates.

In testimony whereof I affix my signature in presence of two witnesses.

CHARLES COPPOCK.
